United States Patent Office

Des. 202,882
Patented Nov. 16, 1965

202,882

VEHICLE

Thomas J. Dunn, P.O. Box 110, Hackettstown, N.J.

Filed Dec. 9, 1964, Ser. No. 82,967

Term of patent 14 years

(Cl. D14—3)

Fig. 1

Fig. 2

Fig. 3

FIGURE 1 is a frontal perspective view of a vehicle showing my new design;

FIGURE 2 is a front elevational view thereof;

FIGURE 3 is a rear elevational view thereof;

FIGURE 4 is a top plan view thereof; and

FIGURE 5 is a side elevational view thereof.

The dominant features of the design reside in the portions shown in full line in the drawings.

I claim:

The ornamental design for a vehicle, substantially as shown and described.
